[57] CLAIM

The ornamental design for combined ceiling fan motor and switch housing and blade iron unit, as shown and described.

DESCRIPTION

FIG. 1 is a bottom perspective view of combined ceiling fan motor and switch housing and blade iron unit of my new design;

FIG. 2 is an enlarged side elevational view thereof and with other side views being substantially identical;

FIG. 3 is an enlarged bottom plan view thereof; and,

FIG. 4 is an enlarged top plan view thereof;

The broken line showing of fan blades and a support rod is for illustrative purposes only and forms no part of the claimed design.

Two of the blade irons have been shown broken away in FIGS. 3 and 4 for ease of illustration.
